UNITED STATES PATENT OFFICE

172,523

SPOTLIGHT HOUSING OR SIMILAR ARTICLE

Philip G. Stone, Newark, N. J.

Application December 24, 1953, Serial No. 28,196

Term of patent 14 years

(Cl. D48—20)

To all whom it may concern:

Be it known that I, Philip G. Stone, a citizen of the United States, residing in the city of Newark, county of Essex and State of New Jersey, have invented a new, original, and ornamental Design for a Spotlight Housing or Similar Article, of which the following is a specification, reference being had to the accompanying drawing, forming a part hereof:

Figure 1 is a side elevational view of a spotlight housing or similar article, showing my new design;

Figure 2 is an elevational view showing the side opposite Figure 1;

Figure 3 is a top plan view thereof;

Figure 4 is a bottom plan view thereof;

Figure 5 is a front end elevational view thereof; and

Figure 6 is a rear end elevational view thereof.

I claim:

The ornamental design for a spotlight housing or similar article, as shown.
